UNITED STATES PATENT OFFICE.

JAMES C. BLAIR, OF TOLEDO, OHIO, ASSIGNOR TO THE LIBBEY-OWENS SHEET GLASS COMPANY, OF TOLEDO, OHIO, A CORPORATION OF OHIO.

ANNEALING LEER.

Application filed January 13, 1926. Serial No. 80,874.

The present invention relates to an annealing leer, and has particular reference to a leer well adapted for the annealing of sheet glass.

5 An important object of the invention is to provide a sheet glass annealing leer wherein the sheet to be annealed passes through a plurality of zones.

10 A further object of the invention is to provide a sheet glass annealing leer wherein a plurality of baffle plates are arranged within the leer and above the sheet, the said baffle plates depending from the top of the leer to create a plurality of zones.

15 A further object of the invention is to provide a leer of this nature wherein a plurality of baffle plates depend from the top of the leer, the baffle plates being progressively shorter from the hot end of the leer toward

20 the cold end thereof.

in the Colburn Patent 1,248,809, granted December 4, 1917. In this patent a sheet of glass is drawn from a draw-pot. It is deflected over a bending member, passed over a flattening table and through an annealing leer. The leer at the end which the sheet enters is known as the hot end, and is relatively much hotter than the opposite end which is known as the cutting table end. The temperature of the leer is gradually reduced so that the sheet which is formed from molten glass of a high temperature is gradually reduced to room temperatures to relieve strains, etc.

25 The present application has particular reference to a new form of annealing leer. In the drawings the numeral 10 designates the drawing chamber which includes the flattening table 11 and draw bar arrangement 12, both of which constructions are 30 shown diagrammatically. The annealing leer 13 is provided with a plurality of rotatable rolls 14 which support and convey the sheet of glass 15 through the leer. The end 16 is the hot end, and the end 17 is the 35 cutting table end. The length of the leer 13 may vary, although ordinarily it will range between 200 to 300 feet. The sheet 15, after being annealed, is passed out upon a table 18 where it may be cut into the desired lengths.

40 In accordance with the present invention a plurality of baffle plates 19 are arranged within the leer and are adapted to depend from the top 20 of the leer. The baffles may be of any desired material and are arranged to divide the leer into a plurality of zones. The baffle plates become progressively shorter from the hot end 16 toward the cutting table end 17. With this arrangement the first few compartments are more or less distinct, their borders being clearly defined by the baffle plates, while the other compartments are divided but slightly.

45 Arranged beneath the sheet, and especially at the hot end 16, are a plurality of heating means 21 which may be in the form of gas burners, electrical resistance units, etc.

50 In Fig. 1 the baffle plates 19 are shown as being rigid, while in Figs. 3, 4 and 5, they are adjustable. In Fig. 3 the baffle comprises the sections 22 and 23, the section 22 being rigidly associated with the top 20 and having means whereby the section 23 may be pivotally supported thereby. An operating

55 Other objects and advantages of the invention will become apparent during the course of the following description.

60 In the drawings wherein like numerals are employed to designate like parts throughout the same,

Fig. 1 is a vertical longitudinal section of a leer formed in accordance with my invention,

Fig. 2 is a section taken on line 2-2 in Fig. 1, and

Fig. 3, 4 and 5 are fragmentary sectional views of slightly modified forms of construction.

65 In the production of glass articles, including sheet glass, it is necessary, after the articles have been formed, to subject them to suitable annealing temperatures. In sheet glass machines this is accomplished by passing the sheet of glass through an annealing leer.

70 The type of leer shown in the drawings is similar to the leer used on the Colburn machine, which is more specifically set forth

lever 24 may be used to adjust the angularity of the lower section 23, while a clamping member 25 may be used to maintain the desired adjustment.

5. In Fig. 4 the baffle 26 is operable through an opening 27, by which means a cable or the like 28 may be used to elevate or lower the baffle to attain the proper position. In Fig. 5 the baffle 29 is in the form of a butterfly 10 valve and is operable through means of the lever 30.

Of course there are a great many other forms of modifications which could be used, and therefore it is to be understood that I 15 do not wish to limit myself to the particular type of baffle plate to be used. The invention resides in the fact that the annealing leer is divided into a plurality of zones of different temperatures by means of baffle 20 plates, the baffle plates being preferably but not necessarily arranged so that they become progressively shorter from the hot end of the leer toward the cutting table end. With this type of apparatus the annealing 25 of the glass sheet can be accurately controlled, thus reducing to a minimum breakage within the leer during the annealing period.

It is to be understood that the form of the 30 invention herewith shown and described is to be taken as the preferred embodiment of the same, and that various changes in the shape, size and arrangement of parts may be resorted to without departing from the 35 spirit of the invention or the scope of the subjoined claims.

Claims:

1. In sheet glass apparatus, an annealing 40 leer, a plurality of baffles therein positioned at one side of the sheet and heating means also within the leer at the opposite side of said sheet.

2. In sheet glass apparatus, an annealing 45 leer, a plurality of baffles therein positioned at one side of the sheet, said baffles varying in heights and heating means also within the leer at the opposite side of said sheet.

3. In sheet glass apparatus, an annealing 50 leer, means at one side of the sheet for dividing said leer into a plurality of zones, and heating means also within the leer at the opposite side of said sheet.

4. In sheet glass apparatus, an annealing 55 leer, a plurality of baffles arranged therein at one side of the sheet for dividing said leer into a plurality of zones, and heating means also within the leer at the opposite side of said sheet.

5. In sheet glass apparatus, an annealing 60 leer, a plurality of various sized baffles arranged therein at one side of the sheet for dividing the leer into a plurality of zones,

and heating means also within the leer at the opposite side of the sheet.

6. In sheet glass apparatus, an annealing 65 leer, a plurality of baffles arranged therein and depending from the top of the leer and burners also within the leer and positioned beneath the sheet.

7. In sheet glass apparatus, an annealing 70 leer, means for supporting a sheet therein, a plurality of baffles arranged above the sheet for dividing the leer into zones and a plurality of burners arranged within the leer beneath said sheet. 75

8. In sheet glass apparatus, an annealing leer, means for supporting a sheet therein, a plurality of baffles arranged above the sheet for dividing the leer into lengths, the baffles varying in lengths and burners arranged within the leer beneath said sheet. 80

9. In sheet glass apparatus, an annealing leer, means for supporting a sheet therein, a plurality of baffles arranged above the sheet and being progressively shorter from 85 the hot end of the leer toward the cold end thereof and a plurality of burners arranged within the leer beneath said sheet.

10. In sheet glass apparatus, an annealing leer, means for supporting a moving sheet 90 therein, a plurality of baffle plates arranged above the sheet and depending from the top of said leer, and adapted for separating the leer into zones, said baffles being progressively shorter from the hot end toward the 95 cold end of the leer and a plurality of burners arranged within the leer beneath the sheet and positioned at spaced points longitudinally of said leer.

11. In sheet glass apparatus, an annealing 100 leer, means for supporting a moving sheet of glass therein, a plurality of adjustable baffle plates therein for dividing the leer into zones above the sheet, and heating means beneath the sheet for supplying heat to said 105 zones.

12. The process of annealing sheet glass, consisting in passing the sheet through a leer comprising a plurality of heated compartments above the sheet, the temperature 110 of the compartments being controlled by heating means beneath the sheet and being progressively lower from the end of the sheet enters the leer toward the end the sheet leaves the leer. 115

13. The process of annealing glass consisting in passing the glass horizontally through an annealing oven divided above the glass into a plurality of zones supplied with heat from means beneath said glass. 120

Signed at Toledo, in the county of Lucas, and State of Ohio, this 9th day of January, 1926.

JAMES C. BLAIR.

CERTIFICATE OF CORRECTION.

Patent No. 1,655,935.

Granted January 10, 1928, to

JAMES C. BLAIR.

It is hereby certified that error appears in the printed specification of the above numbered patent requiring correction as follows: Page 2, line 113, claim 12, strike out the word "of"; and that the said Letters Patent should be read with this correction therein that the same may conform to the record of the case in the Patent Office.

Signed and sealed this 10th day of April, A. D. 1928.
